UNITED STATES PATENT OFFICE.

ADDISON CLUTTER, OF HOMER, ILLINOIS.

DESIGN FOR A BRACKET.

No. 39,418.

Specification for Design.

Patented July 14, 1908.

Application filed April 16, 1908. Serial No. 427,542. Term of patent 14 years.

To all whom it may concern:

Be it known that I, ADDISON CLUTTER, a citizen of the United States, residing at Homer, in the county of Champaign and State of Illinois, have invented a new, original, and ornamental Design for Brackets, of which the following is a specification, reference being had to the accompanying drawing, forming part thereof.

The figure is a front elevation of a bracket, showing my new design.

I claim:

The ornamental design for a bracket, as shown.

ADDISON CLUTTER.
